SLIDE OPERATED FASTENER INSTALLATION

Samuel Esserman, Brooklyn, N. Y.

Application November 17, 1937, Serial No. 175,161

5 Claims. (Cl. 24—205)

The invention relates particularly to closing articles of apparel made of such materials as furs, knitted goods or other fabrics which have more or less long, exposed filaments such as hairs or threads. The invention may also be of use to attach together the edges of such materials wherever they occur or are useful. For this purpose it is proposed to use separable slide operated fasteners of usual or standard types. One of the deterrents to the employment of such fastening means with materials such as indicated has been that the exposed or projecting filaments whether they be hairs or threads tend to become entangled with the slide member or the fastening elements or both. This ordinarily causes deterioration or injury to the fabric by disturbance, dislocation and binding of the filaments. Another or additional inconvenience in such installations lies in the fact that the filaments, whether hairs or threads, when engaged by the fastening elements or the sliding members tend to interrupt the operation of the mechanism. It frequently is necessary to stop the movement of the slide member for instance, and reverse it so as to free the filaments and then carefully hold them out of the path of the slide and the fastening members. This is a considerable inconvenience and has resulted in a limited use of slide fasteners in connection with such materials.

The present invention has to do with avoiding these defects and inconveniences. It has been discovered that it is possible to employ separable fastening means of the slide operated type with such materials if there is interposed between the material to be fastened and the sliding member some means for turning the edges and the projecting filaments of the materials to be fastened away from the sliding member. This may be accomplished in numerous ways such, for instance, as applying a free edged intermediate member which shall be flexible but of sufficient stiffness to be itself moved or lifted by the sliding member and at the same time lift and push out of the way the overlying material which is to be fastened. In some instances it is found especially convenient to make the exposed edge of the intermediate member corded to add strength to it and give it the necessary operating characteristics.

In the accompanying drawing Figure 1 is a fragmentary plan view of a portion of a closure of fur or furlike material. Fig. 2 is a transverse vertical section on the line 2—2 of Fig. 1. Fig. 3 is a fragmentary plan view of closing mechanism applied to such material as woolen knitted goods

having long extending threads or filaments. Fig. 4 is a transverse vertical section through such a construction as Fig. 3, the sliding fastener operating member being indicated in position.

As indicated in Fig. 1 the fur members 10 and 11 may be, if desired, so placed that they substantially abut each other and their filaments or hairs cross and interlock at their meeting edges. On the lining or inner side of the members 10 and 11 are fastened the usual tapes 12 and 13 carrying at their edges separable fastener members 14 and 15. The separable fastener members are operated to open and close by the usual sliding member 16 provided with a thumb tab or handle 17. Interposed between the tape 12 and the material 10 is a longitudinal member 18 which may extend outwards over the fastener members 14 and also extends over and lies upon the sliding member 16. At its upward edge the member 18 may be corded as at 19. A similar member 20 which may be corded at 21 is similarly inserted between the tape 13 and the material 11. The material 10 and 11 is here illustrated as extending partially over the cord members 19 and 21 although when desired it may be extended over and may actually overlie the cord members 10 and 21, thus extending over the slide member 16. Such an arrangement may be bulky, however, and may tend to form a bumpy meeting line for the materials 10 and 11. Even when these materials are set back slightly as indicated in Fig. 2 the loose filaments or hairs 22 and 23 on the respective members 10 and 11 may overlap and interlock when the device is closed so as to more or less effectively conceal the separable fastener members 14 and 15. While this may be a desirable arrangement it is not essential to the present invention. At the adjacent edges of the members 10 and 11 the filaments or hairs 22 and 23 being arranged helter-skelter and not in orderly fashion may and generally do extend or droop or fall into or against the separable fastener members 14 and 15 and may thus be engaged by them as well as by the sliding member 16. Such arrangement might normally interfere with the operation of the fastening mechanism but the members 18 and 20 are moved and lifted by the underlying slide member 16 and the members 18 and 20 in turn lift the adjacent edges of the members 10 and 11 and so push or throw the filaments or hairs 22 and 23 up and away from the fastener members 14 and 15 and more or less out of the path of the sliding member 16. The members 18 and 20 are flexible but sufficiently stiff or semi-rigid to cause the materials 10 and 11 to be lifted

or raised away from the fastening members slightly in advance of the sliding member 16 so that the hairs or filaments are pulled out of position to be engaged by the closing fasteners and likewise out of position to be engaged by the sliding member 16. This lifting or clearing operation may be aided by cording or otherwise specially stiffening the edges of the members 18 and 20 while still leaving them sufficiently flexible for operation. There may be thus formed around the sliding member 16 a small tent-like structure by the members 18 and 20 being lifted at the contact of the sliding member 16 and gradually tapering off in advance thereof to contact with the separable fastening members 14 and 15. At this point in advance of the sliding mechanism there is a clear free portion of the separable fastener members substantially entirely free from filaments from the members 10 and 11. The sliding member is thus always free to move without interference or obstruction by the filaments 22 and 23 and the separable fastener members 14 and 15 at the point where they are joined or connected are likewise substantially free from contact with or interference by the filaments 22 and 23 which are thus kept from being entangled.

In Figs. 1 and 2 an effort has been made to illustrate the invention applied to joining pieces of fur or other materials which have fairly long hairs or filaments and in which the hairs or filaments in the closed position may substantially hide or conceal the underlying closing members. In Figs. 3 and 4 the closing members are illustrated as so arranged as to more or less clearly appear between the edges of the members which are to be attached and they are illustrated in connection with fabrics 23 and 24 the edges of which are set somewhat back from each other and which may be provided with shorter threads or hairs such as may occur in knitted articles or the like. Intermediate members 18a and 20a are here illustrated as tapes of more or less rigid but somewhat flexible material which have sufficient inherent strength to perform the desired function without corded edges.

In the claims the clause "flexible sheet material having fur-like filaments projecting from at least one surface" is employed to indicate fur or knitted goods, or fabrics, or other materials having fairly long hairs or filaments.

The invention is not confined to the specific matter illustrated and described but may be embodied in other forms.

I claim as my invention:

1. In combination with the adjacent edges of flexible sheet material having fur-like filaments projecting from at least one surface, a pair of tapes one secured to each edge of the material and carrying interlocking elements, an operating slider for causing the elements to engage and disengage and having a portion slidable between the

interlocking elements and the edges of the sheet material, and a pair of longitudinal strips secured between the sheet material and the tapes and overlying a portion of the engaging members and a portion of the slider so that the filaments are kept from engagement with the interlocking elements. 5

2. In combination with the adjacent edges of flexible sheet material having fur-like filaments projecting from at least one surface, a pair of 10 tapes one secured to each edge of the material and carrying interlocking elements, an operating slider for causing the elements to engage and disengage and having a portion slidable between the interlocking elements and the edges of the sheet material, and means between the sheet material and the tapes and overlying at least a portion of the slider so that the filaments are kept from engagement with the interlocking elements. 15

3. Means for fastening adjacent edges of flexible sheet material having fur-like filaments projecting from at least one surface comprising a pair of tapes adapted to be secured one to each edge of the material and carrying interlocking elements, an operating slider for causing the elements to 20 engage and disengage and having a portion adapted to slide between the interlocking elements and the edges of the sheet material, and means adapted to lie between the sheet material and the tapes and to overlie at least a portion of the slider so that the filaments are kept from engagement with the interlocking elements. 25

4. Means for fastening adjacent edges of flexible sheet material having fur-like filaments projecting from at least one surface comprising a pair of tapes adapted to be secured one to each edge of the material and carrying interlocking elements, an operating slider for causing the elements to engage and disengage and having a portion adapted to slide between the interlocking 30 elements and the edges of the sheet material, and a pair of longitudinal strips adapted to lie between the sheet material and the tapes and to overlie at least a portion of the slider so that the filaments are kept from engagement with the interlocking elements. 35

5. Means for fastening adjacent edges of flexible sheet material having fur-like filaments projecting from at least one surface comprising a pair of tapes adapted to be secured one to each edge of the material and carrying interlocking elements, an operating slider for causing the elements to engage and disengage and having a portion adapted to slide between the interlocking elements and the edges of the sheet material, and a pair of longitudinal strips having a corded free edge and adapted to lie between the sheet material and the tapes and to overlie at least a portion of the slider so that the filaments are kept from engagement with the interlocking elements. 40
